Joseph Peltnam of Salem Massachusetts Sellers Patent

The Schedule referred to in these Letters Patent and making part of the same containing a description in the words of the said Joseph Peltnam himself of his improvement in the method of making from Clay or other compositions of malleable Slabs, fire fire Backs, Stone linings Circular Bricks with tongue and groove to match so as to form a cylinder for lining Stoves, making drains, &c.

To all persons to whom these Presents shall come. Joseph Peltnam of Salem in the County of Essex and State of Massachusetts, sends Greeting. Be it known that I the said Joseph Peltnam have invented and constructed made and applied to use, a new and useful improvement in the method of making from Clay or other compositions of malleable Slabs, fire fire Backs, Stone linings Circular Bricks with tongue and groove to match so as to form a cylinder for lining Stoves, or for making Small drains or water conductors, together with various other articles of any shape or form required, by the use of moulds, constructed and used in the manner following Viz.

1° A Platform made of Planks of suitable dimensions, to contain the moulds to be used, one side and one end of the plank to have cleats nailed strong against the plank rising two or three inches above the surface, the opposite side and end of the plank to have cleats nailed down strong and at a sufficient distance from the first named cleats, to admit the moulds with block between the moulds and the last mentioned cleats, so that when the mould is placed on the Platform against the first mentioned cleats, the parts of the mould may be wedged between the cleats and held firm. 2d. The bottom part of the mould to be in the form of the article required to be made with berels, notches, grooves, sunken or in relief.

3° If the pieces or blocks that form the grooves, notches, or berels should not be confined to the bottom but should be removed from the mould when discharged from the mould. If the sides of the mould to

Drawings attached

be in separate pieces and to bear against the sides of the bottom ^{make} piece
being high enough above the bottom to make the article the thickness
required. 5th If the sides of the article is required to be
rounded or in any other shape the side pieces of the mould should
be made so as to give the article the form required. With the
bottom part of the mould to be covered with cloth and the side
pieces bound to prevent the mortar from adhering. 6th The
mortar to be in as hard a consistency as will admit of the parts being
well united. 8th The mould to be partly filled and bound down
with a mallet or pounder so as to fill the corners at the bottom
then the mould to be filled up by slopping mortar on with the
hand so as to make the parts unite, the surplus mortar to be
knocked off and the article smoothed. 9th When the article is formed
the wedge and blocks to be removed, the sides of the mould
taken off the article to be carried on the bottom piece of the mould
and turned up on the wedge, the bottom removed and left to dry.

Inviting you that the above is a true specification of my said
improvement as above described. I have here set my hand the
second day of June A.D. 1835
